US00D942079S

(12) **United States Design Patent** (10) **Patent No.:** **US D942,079 S**
(45) **Date of Patent:** **** Jan. 25, 2022**

(54) **SHAVER**

(71) Applicant: **KONINKLIJKE PHILIPS N.V.**,
Eindhoven (NL)

(72) Inventor: **Gael Louis Jacques Prat-Pfister**,
Amersfoort (NL)

(73) Assignee: **KONINKLIJKE PHILIPS N.V.**,
Eindhoven (NL)

(**) Term: **15 Years**

(21) Appl. No.: **29/700,483**

(22) Filed: **Aug. 2, 2019**

(30) **Foreign Application Priority Data**

Feb. 4, 2019 (EM) 006156618-0005

(51) **LOC (13) Cl.** **28-03**

(52) **U.S. Cl.**

USPC **D28/50**

(58) **Field of Classification Search**

USPC D28/50, 54

CPC B26B 19/3853-3866; B26B 19/14-18

See application file for complete search history.

reviewed as early as Jun. 2020 (Year: 2020).*

Primary Examiner — Jennifer Rivard

(57) **CLAIM**

The ornamental design for a shaver, as shown and described.

DESCRIPTION

FIG. 1 is a perspective view showing the first embodiment of my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view showing the second embodiment of my design;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view showing the third embodiment of my design;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof;

FIG. 21 is a bottom plan view thereof;

FIG. 22 is a perspective view showing the fourth embodiment of my design;

FIG. 23 is a front elevational view thereof;

FIG. 24 is a rear elevational view thereof;

FIG. 25 is a right side elevational view thereof;

FIG. 26 is a left side elevational view thereof;

FIG. 27 is a top plan view thereof; and,

FIG. 28 is a bottom plan view thereof.

The broken lines illustrate a portion of the shaver and form no part of the claimed design.

1 Claim, 16 Drawing Sheets
